Nelson M. Howard

UNITED STATES PATENT OFFICE.

THOMAS BAGGOT CLARKE, OF LEICESTER, ENGLAND, ASSIGNOR TO UNITED SHOE MACHINERY CORPORATION, OF PATERSON, NEW JERSEY, A CORPORATION OF NEW JERSEY.

HEEL-FEEDING DEVICE FOR MACHINES FOR OPERATING ON HEELS.

1,377,315.

Specification of Letters Patent. Patented May 10, 1921.

Application filed July 3, 1918. Serial No. 243,129.

To all whom it may concern:

Be it known that I, THOMAS B. CLARKE, a subject of the King of Great Britain, residing at Leicester, England, have invented 5 certain Improvements in Heel-Feeding Devices for Machines for Operating on Heels, of which the following description, in connection with the accompanying drawings, is a specification, like reference characters on 10 the drawings indicating like parts in the several figures.

This invention has reference to heel-feeding devices for machines of the class (such for example as heel-compressors) used for 15 operating upon heels.

Heel-compressing machines customarily have a feed slide carrying clamping members which engage the heel by its opposite sides and it sometimes occurs, especially 20 with high heels, that a heel placed by the operator in the clamp enters between the dies and plunger in a tipped condition and becomes mutilated and may even lead to some damage to the machine. This mis- 25 placement of the heel may be attributable to an occasional tendency of the operator to introduce the heel into the clamp in an inclined direction, or to the inertia of the more or less topheavy heel as the slide ad- 30 vances smartly, or to the failure of the operator to seat the heel snugly between the side clamping members; or to a combina- 35 tion of these causes.

Having as an important object the elimination of this trouble, the invention provides the operator with exceptional facilities for introducing the heel in the correct position, and acts positively to right the heel if it is held incorrectly by the clamp, 40 as has been mentioned above, and to support it against displacing tendencies during the feed.

One feature of the invention resides in a machine of the class described, in the provision, in combination, of means for performing the desired operation upon the heel, a heel-clamp which receives movement to bring the heel into operative relationship to said means and a part adapted to act on the 45 lateral surface or edge of a misplaced heel held by the clamp and automatically to right the heel for the operation.

A further feature of the invention consists in the combination of a heel-feed slide

carrying side heel-clamping members and a 55 part arranged to engage the end of the heel remote from the operating position to which the heel is fed, said part being mounted for tipping movement toward the heel about an axis extending transversely of the line of 60 feed and of the height of the heel.

Other objects and features of the invention which include certain improved combinations of parts will become evident to those skilled in the art from the following 65 description of a preferred form of the invention, when read in connection with the accompanying drawings, in which:

Figure 1 is a plan view of a part of the heel feeding slide of a well-known type of 70 heel-compressing machine;

Fig. 2 is a mid-sectional elevation of the part of the slide shown in Fig. 1; and

Fig. 3 is a perspective view, upon a somewhat larger scale, of a detail of the parts 75 shown in Fig. 1.

Referring now to the drawings:

Upon the slide 2 are pivoted the usual side clamp-arms, 4, 6. These arms are interconnected by gear segments on arms 8, 10 80 rigid with the arms 4, 6 respectively. The arm 4 has an extension 12 which connects with suitable mechanism by which the clamp is opened on its return to heel-receiving position and closed on its advance toward compressing position.

These parts are substantially as disclosed in Patent No. 776,823, granted Dec. 6, 1904 upon the application of C. L. Allen, to which patent reference may be had for a 90 complete disclosure of details of construction which it is not necessary to describe specifically here.

On a forwardly-projecting portion 14 of the part 2 is mounted an adjustable carrier 28, locked in position by screws 16, 18 with interposed washers 20, and a pin 32 projecting from the part 14 into one of a series of holes 30. The screws 16, 18 pass through slots 24, 26. The carrier 28 affords 100 pivotal support for the reduced ends 34, 36 of the boss 38 of a bell-crank lever comprising a heel-end engaging plate 40 and a heavy tail 42 which, when unsupported, throws the plate 40 into the position shown 105 in Fig. 3, this being the position when the slide is in heel-receiving position. Although the plate is relatively high and can, when

in operative position, effectively locate and support a high heel, the position which it thus assumes is such that there is a minimum of obstruction to the quick and accurate introduction of the heel into the clamp by the operator. When the feed slide advances (toward the left in the drawing) the side clamping members close on the heel and then the tail 42 runs on to a fixed portion 43 of the slide carrying head (there being a recess 44 in the part 14 to receive the tail) and the plate 40 is rocked or tipped forward into position to support the heel at its end until at the end of the slide travel, the heel is released by the side clamping members. Any heel which may have been grasped by the side clamping members in a tipped position is thus righted into the proper position to be operated upon as desired.

Having thus described my invention what I claim as new and desire to secure by Letters Patent of the United States is:—

1. In a machine of the class described, the combination of a heel-clamp having heel-feeding movement, an abutment engaging a lateral face of the heel for locating the heel during the feed, and means acting during the feed to move the abutment automatically toward the heel relatively to the clamp about an axis extending transversely of the height of the heel.

2. In a machine of the class described, the combination of clamping members for engaging respectively the opposite sides of a heel, a feeding slide carrying said clamping members, a member arranged to engage the end of the heel remote from the operating position to which the heel is fed, and means for advancing the last-named member relatively to the clamping members in the direction of feed after the heel has become engaged by said clamping members.

3. In a machine of the class described, the

combination of a heel-feed slide carrying side heel-clamping members and a part for engaging the heel-end remote from the operating position to which the heel is fed, said part being pivoted for rocking movement about an axis extending transversely of the line of feed and of the height of the heel, and means for rocking said part into heel-supporting position as said slide moves toward the operating position.

4. In a machine of the class described, the combination of a heel feed slide carrying heel clamping members, a part for engaging the heel end remote from the operating position to which the heel is fed, said part being mounted for tipping movement toward a heel, and means in the path of movement of said part for tipping it toward a heel between the clamping members during the feeding movement.

5. In a machine of the class described, the combination of a heel clamp having heel feeding movement and a heel edge engaging member movable with the clamp and actuated by the movement of the clamp to right a misplaced heel in the clamp.

6. In a machine of the class described, the combination of a heel clamp having heel feeding movement, a heel breast abutment movably connected to the clamp, and means actuated by the movement of the clamp for rocking the abutment to right a misplaced heel in the clamp.

7. In a machine for operating upon heels, the combination of a heel clamp having heel feeding movement, a member movable with the clamp, and means operated by the movement of the clamp to rock the member relatively to the clamp about an axis transverse to the path of movement of, and toward the rear of, the clamp.

In testimony whereof I have signed my name to this specification.

THOMAS BAGGOT CLARKE.
